UNITED STATES PATENT OFFICE

158,430

TOASTER

Fred Bertino, Flushing, N. Y.

Application November 10, 1949, Serial No. 5,977

Term of patent 14 years

(Cl. D81—10)

To all whom it may concern:

Be it known that I, Fred Bertino, a citizen of the United States, residing at Flushing, in the county of Queens and State of New York, have invented a new, original, and ornamental Design for Toaster, of which the following is a specification, reference being had to the accompanying drawing, forming a part thereof.

This application is a continuation in part of my copending application, Serial No. D. 143,016, filed December 6, 1947, for Electric pop-down toasters.

Figure 1 is a perspective view of a toaster embodying the design of the invention.

Figure 2 is a side elevation of Figure 1, a portion of one of the handles being broken away. The handle broken away is like that shown com-

plete. The opposite side has the same appearance as Figure 2.

Figure 3 is a top plan of Figure 1.

Figure 4 is an end elevation of Figure 1, the opposite end having the same appearance as Figure 4.

I claim:

The ornamental design for a toaster, as shown and described.

FRED BERTINO.
